UNITED STATES PATENT OFFICE.

WILLIAM R. SMITH, OF FREDRIC, IOWA.

ATTACHMENT FOR MOTOR-CARS.

1,319,806.

Specification of Letters Patent. Patented Oct. 28, 1919.

Application filed February 4, 1919. Serial No. 274,886.

To all whom it may concern:

Be it known that I, WILLIAM R. SMITH, a citizen of the United States, residing at Fredric, in the county of Monroe and State 5 of Iowa, have invented certain new and useful Improvements in Attachments for Motor-Cars, of which the following is a specification.

This invention relates to attachments for 10 motor cars which permit the cars to be used as stationary engines for driving machinery; and it consists in the novel construction and combination of the parts hereinafter fully described and claimed.

15 In the drawings, Figure 1 is a side view of an attachment constructed according to this invention. Fig. 2 is a plan view of the same. Fig. 3 is an end view of the attachment. Fig. 4 is a detail view of the rear 20 end portion of the shaft and the stub shaft which engages with the motor shaft of the car.

The attachment is specially adapted for use with the cars known as "Ford" cars, but 25 it may be used with any other make of car to which it can be applied.

The radiator portion 2 of a car at the front end thereof, and a portion of the motor shaft 3, are shown. The motor shaft 30 3 has a cross-pin 4, and the radiator casing or an extension of its front plate frequently has a hole 5' in front of the end of the motor shaft for the insertion of the usual starting device which engages with the motor shaft 35 and the pin 4. In a "Ford" car the motor shaft 3 is arranged in line with a space or opening under the radiator and between it and the axle and springs.

In carrying out this invention a shaft 5 40 is provided, and is journaled in bearings 6 on a supporting frame or base 7. The shaft 5 is arranged axially in line with the motor shaft 3, and the base 7 is supported from the radiator casing or any other convenient portion 45 of the car by means of detachable brackets 8. The shaft 5 is adjustable longitudinally in its bearings, and 9 is a collar provided with a removable set-screw 10 for securing it to the shaft 5. This collar bears 50 against the front shaft bearing, and prevents the shaft from sliding forwardly when secured to it by the set-screw.

The rear end portion of the shaft 5 has a 55 cylindrical chamber 12 formed in it, and this chamber has longitudinal slots 14 at its sides. A stub shaft 15 is provided, and its

front end portion 16 is slideable longitudinally in the chamber 12, and it has a cross-pin 13 for engaging with the slots 14. The stub shaft 15 is thrust through the hole 5' 60 in the extension of the front plate of the radiator casing, and it has a collar 17 secured on it. A helical spring 18 encircles the stub shaft, and is arranged between the radiator casing and the collar 17. The rear 65 end portion of the stub shaft 15 is provided with a cup or socket 20 having longitudinal slots 21 for engaging with the motor shaft 3 and its cross-pin 4.

The front end portion 24 of the shaft 5 70 is reduced in diameter, and is provided with a cross-pin 25. A starting crank 26 of any approved make is provided, and its hub 27 is slideable on the shaft extension 24, and it has a clutch 28 for engaging with the cross-pin 25 in the way usual with starting cranks.

A fast pulley 30 and a loose pulley 31 are mounted on the front end portion of the shaft 5, and a driving pulley 33 is secured on the middle part of the shaft between the 80 shaft bearings.

A fan 35 is provided, and is secured on a fan shaft 36, which is journaled in a bearing 37 secured to the rear bearing of the shaft 5. The fan shaft is arranged parallel to the 85 shaft 5, and the fan is arranged in front of the radiator so that the blast is directed against the radiator and the motor of the car. A belt pulley 38 is secured on the front part of the fan shaft 36, and 39 is a belt 90 which passes over the pulleys 33 and 38 and drives the fan from the shaft 5. The pulley 38 is made with a broad face to allow for the sliding movement or adjustment of the shaft 5. Any other approved driving mechanism 95 may be used for operatively connecting the shaft 5 with the fan shaft.

When the motor car is stationary it may be used to drive any sort of machinery by means of the fast and loose pulleys 30 and 100 31 and any suitable driving belt. The power is taken directly from the motor shaft, which is preferably unclutched from the transmission gearing of the car. The blast of air from the fan cools the radiator and the engine, and enables the full power of the gasoline engine or other motor to be used. When the car is stationary the radiator is not cooled by being moved through the air, and the full power of the motor is restricted by the liability 105 of the motor to become overheated.

When the attachment is to be used, the

collar 9 is secured to the shaft 5 so that the cup or socket 20 of the stub shaft engages with the motor shaft, the shaft 5 being pushed rearwardly by hand against the pressure of the spring 18 before the collar 9 is fastened by its set-screw.

The attachment does not have to be removed from the car when the car is run, and the attachment is not required to drive 10 machinery. The collar 9 is simply loosened on the shaft 5, and the spring 18 on the stub shaft pushes forward the shaft 5 so that the cup or socket 20 is held detached from the motor shaft. The motor 15 can be started as often as necessary, by pushing the shaft 5 rearwardly without fastening the collar 9, and then cranking the engine by the crank 26.

The extension 24 of the shaft 5 which 20 fits the starting crank hub is made of the same size as the front end portion 16 of the stub shaft, so that if it is desirable to remove the attachment altogether, the starting crank 26 can be applied to the 25 front end portion 16 of the stub shaft. The car can be driven with or without the fan in operation, as found desirable, but it is usually satisfactory to drive the car without the fan blast, as its cooling action is 30 less essential when the car is in motion, and the full load on the engine is more intermittent than when the engine is required to operate at its full power in driving machinery.

35 What I claim is:

1. An attachment for a motor car, comprising a frame provided with means for securing it to a car and having a front bearing and a rear bearing, a shaft slidable 40 longitudinally and revoluble in the said

bearings and provided at its rear end with means for engaging the motor shaft, a starting crank for engaging the front end portion of the said shaft, a spring which presses that said shaft forwardly and operates to disengage it from the motor shaft, a slidable collar provided with means for securing it to the said shaft, said collar being adapted to bear against the rear side of the said front bearing and thereby hold 45 the said shaft in engagement against the pressure of the said spring, and means for transmitting power from the said shaft.

2. An attachment for a motor car, comprising a frame provided with means for 50 securing it to a car and having a front bearing and a rear bearing, a shaft slidable longitudinally and revoluble in the said 55 bearings and provided at its rear end with means for engaging the motor shaft, a fan support secured to the said rear bearing, a fan journaled in the said support and provided with a driving pulley, a pulley secured to the said shaft between the front and rear bearings, a belt passing over the 60 said pulleys, a starting crank for engaging the front end portion of the said shaft, a spring which presses the said shaft forwardly and operates to disengage it from the motor shaft, a slidable collar provided 65 with means for securing it to the said shaft, said collar being adapted to bear against the rear side of the said front bearing and thereby hold the said shafts in engagement 70 against the pressure of the said spring, and means for transmitting power from the 75 said shaft.

In testimony whereof I have affixed my signature.

WILLIAM R. SMITH.
